Floyd E. Pettengill, Lancaster, Ohio, assignor to Anchor Hocking Glass Corporation, Lancaster, Ohio, a corporation of Delaware

Filed Jan. 29, 1965, Ser. No. 83,624

Term of patent 14 years

(Cl. D36—8)

FIG. 1 is an elevational view of a tumbler or similar article showing my new design;

FIG. 2 is a bottom plan view thereof.

The characteristic features of my design reside in the portions shown in full lines, which illustrate a series of sets of double bars lying along intersecting diagonal lines wherein successive sets of double bars along a diagonal line are separated by but are in contact with the center of sets of double bars lying along an intersecting diagonal line and wherein said series of sets of double bars are enclosed within spaced horizontal double lines.

I claim:

The ornamental design for a tumbler or similar article, substantially as shown and described.
